UNITED STATES PATENT OFFICE.

HARLAN P. DYE, OF LAKE WORTH, FLORIDA.

DESIGN FOR A BOTTLE.

SPECIFICATION forming part of Design No. 29,615, dated November 8, 1898.

Application filed October 9, 1896. Serial No. 608,417. Term of patent 14 years.

To all whom it may concern:

Be it known that I, HARLAN P. DYE, a citizen of the United States, residing at Lake Worth, in the county of Dade and State of Florida, have invented and produced a certain new and original Design for Bottles; and I do declare the following to be a full, clear, and exact description of the invention, such as will enable others skilled in the art to 10 which it appertains to make and use the same.

The invention relates to a new and original design for bottles; and it consists of a bottle of the configuration shown in the accompanying drawing, which shows elevational and sectional views, Figures 1 and 2, respectively, 15 and in which—

1 denotes the body of the bottle, having a uniform diameter from point *a* to *b*, thence tapering from *b* to *c*, thence projecting upwardly to form the neck *d* of uniform diameter, and having its upper end provided with 20 a curved bulge 2, having a deeply-impressed

external groove 3 to form the sharp shoulder or ledge 3', and the shoulder or ledge 4 of less diameter than the shoulder or ledge 3', said shoulder 4 having a hollow extension 5, which is bulged outwardly at its base, as shown at 25 5', and thence tapered inwardly from the point 5 to the point 5'', thus forming a chamber 7, increasing in diameter from its base to 30 its top and provided with an annular ledge 12.

Within the neck below the chamber and coincident with the groove 3 is an internal groove 8.

What I claim is—

15 The design for a bottle, as herein shown and described.

In testimony whereof I hereunto affix my signature in presence of two witnesses.

HARLAN P. DYE.
